UNITED STATES PATENT OFFICE.

ROBERT CLARKE, OF MOUNT VERNON, OHIO.

ELECTRICAL-SPARK-TIMER DEVICE.

No. 858,956.

Specification of Letters Patent.

Patented July 2, 1907.

Application filed May 28, 1906. Serial No. 319,145.

To all whom it may concern:

Be it known that I, ROBERT CLARKE, of Mount Vernon, in the county of Knox and State of Ohio, have invented certain new and useful Improvements in Electrical-Spark-Timer Devices; and I hereby declare that the following is a full, clear, and exact description thereof, reference being had to the accompanying drawings, which form part of this specification:

This invention is an improved device for regulating the number, time and duration of intermittent electrical currents transmitted in a given time or period, and is particularly adapted for use with the electric spark igniters of internal combustion engines, or whenever mechanically controlled intermittent electrical circuits or impulses are required.

One application and illustration of the invention is shown in the accompanying drawing and shows it built along the lines of the ordinary automobile spark timers or distributors, but embodies the improvements which

20 I desire to protect by Letters Patent.

My improvements are the outcome of various attempts to overcome the many defects in devices of this type, as constructed and used at the present time.

The following is a description of my improved timer 25 as it may be adapted to a four cylinder, four stroke cycle, automobile-gasoline engine.

Figure 1 is a plan view of the device with the cover removed, indicating the electrical circuit diagrammatically. Fig. 2 is a transverse section on line 2—2, Fig. 30 1, also indicating the electrical circuit diagrammatically.

A rotatable shaft A is mounted in suitable bearings— (but one bearing B is shown) and is driven by gears or some other positive method (not shown) at a certain 35 ratio with the crank shaft of the engine (not shown). The top part of shaft A is turned down slightly smaller than the rest, to receive a bracket C which is held thereon by means of nut D and made to revolve with shaft A by the engagement of a pin E with a slot in bracket C, 40 as shown. Bracket C is provided on one end with a pair of ears or lugs X between which is pivoted a lever F on pin G. One end of lever F is provided with a yoke or fork in which is journalled a roller or shoe H on pin I, said roller H has a double beveled periphery. 45 Bracket C is also provided with a third ear or lug X' to which is connected one end of a spring J, the opposite end of which hooks into one end of lever F, as shown. Spring J has the effect of pressing roller H outward away from the center of shaft A and against the surrounding contact rings L, K. This pressure is increased by centrifugal force as the speed of shaft A is accelerated, for when shaft A revolves, bracket C, lever F, pins G and I, roller H, spring J and nut D are carried therewith as a unit.

The parts just mentioned as revolving with shaft A, 55 as well as the surrounding rings K and L are inclosed in case M on top of which is fastened, in a suitable manner, a cover N. Thus the working parts are thoroughly protected. The case may be filled with heavy oil, thoroughly lubricating all parts.

Ring K is pressed into case M and has a stud V threaded and pinned into it which projects through the bottom of case M. A nut or some other suitable device is provided on the outer end of stud V whereof a conductor wire v may be firmly fastened in any suitable 65 manner, and, if so desired, soldered.

Ring L is similar in contour to ring K, but is sawed into eight segments. These eight segments are separated by wood fiber or other suitable insulation as at L', and the entire ring thus obtained, is then pressed 70 into case M above ring K, and is thoroughly insulated from the casing M, ring K and the binding ring Z by a packing P. Then rings K, L, Z, and the interposed packing are pressed down and fastened firmly, by means of four bolts or rivets R, or in some other satisfactory manner, which will leave the four alternate blocks or sections S entirely insulated. To each of the four blocks S is connected a stud T which is threaded and pinned in place, and insulated from case M by means of insulated bushings U. The outer ends of the 75 four studs T are provided with nuts or other suitable devices for firmly fastening wires v' thereto, which wires may be soldered thereto if desired.

It will be noticed that the top inner edge of ring K and the bottom inner edge of ring L are beveled off, thus 85 forming a V-shaped groove which the edge of roller or shoe H engages, said roller being of such shape and size, and is so located that it fits into the V-shaped groove, and rolls with a bearing the full width of its beveled faces, on the beveled portions of both rings K and L. 90

Operation. It is obvious that by revolving shaft A roller H will be made to run around in the V-shaped groove, formed by rings K and L, and will at all times have a perfect contact by its opposite edges with both rings, the full width of its beveled faces. To each of the four studs T a separate wire v' can be attached, leading to a common ground wire v'', which may be connected to a set of batteries v'', or some other source of electricity, the opposite pole of which is connected through the sparking device to the connection V at v. 100 By revolving the shaft A, a regular series of intermittent openings and closings of the circuit will be obtained as roller H passes off and onto the various insulated blocks S, and the current is successively passed through each of the four wires v' connected to studs T. 105 Any desired number of insulated blocks S may be used, from one up, as the case requires, and any number of different wires through which the current may be

successively passed can be connected therewith. By reason of the V-shaped or angular contact produced by causing the wedge shaped roller to run or revolve in a corresponding wedge shaped groove, I obtain all the 5 advantages of the flat roller, namely, good wearing qualities, freedom from uneven and excessive side strains, as well as a large amount of contact surface. By means of the wedging action of the roller, I eliminate the tendency of the roller to jump, in case either 10 of the rings or the roller itself should become roughened.

As the angle of the beveled faces is such that there is at all times a certain amount of slippage at the points of contact, the device has all the advantages 15 of the wipe contact system, namely a tendency to continually keep the contact surfaces clean whereby the best results are produced. The pressure obtained at the points of contact will be greatly in excess of the pressure applied to the contact roller by means of the 20 spring provided for that purpose, hence I obtain a firmer, stronger, thrust or pressure directly at the points of contact with less strain, and consequently, less wear on the balance of the device than it is otherwise possible to obtain.

25 The essential features of my device are—(1) an angular contact between the roller and V-shaped groove or furrow, the roller having a continuous rolling movement; and (2) an angular contact between the roller and V-shaped groove or channel in combination 30 with the ground connection, allowing the current to pass from a contact point or segment through the roller and thence into ground ring and from there into the ground wire, avoiding much loss of current from passing the same through numerous greasy joints, 35 bearings, etc.

With my idea of a direct circulation and ground connection the electric current is passed directly from the wire to the insulated contact point, then onto the roller or other contact point, and from there on, to the 40 ground ring, block, or other device, as the case may be, and thence on to the ground wire attached thereto. This makes it possible to have every joint clean and with the exception of the points of contact, soldered, if so desired.

45 By means of this system it is possible to attain the maximum results with a minimum amount of current (electric), while in a case where batteries are used, it is feasible to use the electric current after a much lower voltage is reached, than would be possible under any 50 other circumstances.

Having described my invention what I claim as new and desire to secure by Letters Patent is:—

1. In an electrical circuit maker and breaker, the combination of a traveling contact roller having beveled edges, a pair of contact rings adjacent the path of said roller and having beveled edges forming a guide groove for the roller, the beveled edge of said roller making a continuous rolling and wiping contact with the beveled edges of said rings. 55
2. In combination, a continuous contact ring having a beveled edge, a series of contact segments adjacent but insulated from said ring and each other, said ring and segments having beveled edges forming a groove, a traveling beveled edge contact roller adapted to travel in said groove and make a rolling and wiping contact with the ring and segments, and means for moving said roller. 60
3. In an electrical circuit maker and breaker, the combination of a rotating contact wheel having beveled edges, a pair of concentrically arranged contact rings surrounding the orbit of said roller, and adapted to be contacted thereby, the beveled edge of said roller making contact with the beveled edges of said rings, one of said rings being divided into insulated sections; a direct electrical circuit connection with one of said rings, and circuit connections with sections of the other ring, substantially as 70 described. 75
4. In combination, a continuous contact ring having a beveled inner edge, a series of contact segments concentric with and insulated from said ring and each other, and having beveled inner edges, an orbitally moving beveled edge roller adapted to make a rolling and wiping contact with the beveled edges of the ring and segments, and means for moving said roller in an orbital circuit and for maintaining contact between it and the ring and segments, substantially as described. 85
5. In an electrical spark timer device, the combination of a rotatable shaft, a spring pressed lever thereon, a bevel edged roller journaled on said lever, a pair of contact rings surrounding the orbit of the roller and having beveled edges forming beveled groove for the guidance of and contact with the roller, one of said rings being continuous, the other divided into insulated sections, a source of electrical energy, a connection between one terminal of said source and the continuous ring, and between the other terminal of said source and the several insulated contact 90 sections, substantially as described. 95
6. In combination, a continuous contact ring having a beveled edge, a series of contact segments adjacent but insulated from said ring and from each other, said segments having beveled edges adjacent the beveled edge of the ring, the beveled portions of the ring and segments forming a groove, an orbitally moving contact device having a beveled edge adapted to travel in said groove and contact with the ring and segments, and means for moving said contact device. 100

In testimony that I claim the foregoing as my own, I affix my signature in presence of two witnesses.

ROBERT CLARKE.
